UNITED STATES PATENT OFFICE

CHARLES LLEWELLYN WILSON, OF BIRMINGHAM, ALABAMA

FUSE

Application filed February 15, 1930. Serial No. 428,811.

This invention relates to fuses employed in protecting circuits to prevent damage to the circuits with which the fuse is associated, should the circuit be shorted.

5 An important object of the invention is to provide a fuse of this character including a removable inner shell in which the fuse wire is mounted, so that the inner shell may be readily removed and replaced when the fuse 10 wire burns out, thereby making it possible to repair a fuse and eliminating the necessity of replacing the entire fuse.

15 A further object of the invention is to provide a fuse which may be cheap to manufacture, and one which may be readily and easily repaired, by persons unfamiliar with mechanics.

With the foregoing and other objects in view, which will appear as the description 20 proceeds, the invention resides in the combination and arrangement of parts and in the details of construction hereinafter described and claimed, it being understood that changes in the precise embodiment of the invention herein disclosed, may be made within 25 the scope of what is claimed, without departing from the spirit of the invention.

Referring to the drawings:

Figure 1 is a vertical sectional view 30 through a fuse constructed in accordance with the invention.

Figure 2 is a plan view thereof.

Referring to the drawings in detail, the fuse comprises an outer shell which includes 35 a metallic body portion 5 and a lower insulating portion 6 constructed of hard rubber or other suitable material.

The reference character 7 designates a brass tip, which is formed with a peripheral 40 groove to receive the flange 8 of the insulating portion 6. The reference character 9 designates the inner or removable section of the fuse which is supplied with an extension 10 adapted to extend through the opening in 45 the brass tip 7, to contact with a contact member of the socket in which the fuse is positioned.

The reference character 11 designates the fuse wire that has one of its ends soldered to 50 the extension 10, the opposite end thereof

being disposed under the metal ring 12 which is positioned over the upper edge of the inner section 9, the outer portion of the ring member being threaded so that the outer shell may be secured in position.

55 Positioned on the inner shell is a metallic ring member 13 which has an inwardly extended flange 14 so constructed that it will grip the translucent cover 15. Secured to the upper portion of the metallic ring member 13, is a finger piece 16 which may be gripped by the operator to place or remove the fuse.

60 From the foregoing it will be seen that due to this construction, the inner removable shell may be disconnected from the device and replaced should the fuse wire 11 burn out, thereby eliminating the necessity of replacing the entire fuse plug.

I claim:

65 In a fuse plug, an outer shell, an inner removable shell, a contact ring positioned over the upper edge of the inner removable shell, a fuse wire within the inner removable shell, one end of the fuse wire being disposed 70 under the contact ring, the opposite end of the fuse wire extending to the inner end of the inner removable shell, and a contact member carried by the inner removable shell and to which the fuse wire is connected. 75

80 In testimony that I claim the foregoing as my own, I have hereto affixed my signature.

CHARLES LLEWELLYN WILSON.
